DUPLEX ELECTRICAL ADAPTER

Ernest R. Carlson, Fairfield, Conn., assignor to Harvey Hubbell, Incorporated, Bridgeport, Conn., a corporation of Connecticut

Application April 22, 1959, Serial No. 55,613

Term of patent 14 years

(Cl. D26—1)

Fig. 1.

Fig. 2.

Fig. 3.

Fig. 4.

Fig. 5.

Fig. 6.

Fig. 1 is a front perspective view of a duplex electrical adapter, showing my new design;

Fig. 2 is a rear perspective view;

Fig. 3 is a front elevational view;

Fig. 4 is a side elevational view;

Fig. 5 is an end elevational view, the opposite end being substantially a mirror image thereof; and

Fig. 6 is a fragmentary cross-sectional view thereof, to an enlarged scale, taken on line 6-6 in Fig. 3.

The dominant features of my new design are shown in solid lines in the drawing.

I claim:

The ornamental design for a duplex electrical adapter, substantially as shown and described.
